UNITED STATES PATENT OFFICE

170,723

SUN TANNING SHIRT

John J. Secosky and Frank J. Sabo, United, Pa.

Application July 20, 1953, Serial No. 26,054

Term of patent 14 years

(Cl. D3—25)

To all whom it may concern:

Be it known that we, John J. Secosky and Frank J. Sabo, citizens of the United States of America, residing at United, in the county of Westmoreland and State of Pennsylvania, have invented a new, original, and ornamental Design for a Sun Tanning Shirt, of which the following is a specification, reference being had to the accompanying drawing forming part thereof.

Figure 1 is a front elevational view of a sun tanning shirt, showing our new design, and

Figure 2 is a rear elevational view thereof.

We claim:

The ornamental design for a sun tanning shirt, as shown.

JOHN J. SECOSKY.
FRANK J. SABO.
